RAIL PULLER AND EXPANDER

Filed Nov. 21, 1931

UNITED STATES PATENT OFFICE

FRANK J. JAKOUBEK, OF ELMWOOD PARK, AND EDMUND PACHOWICZ, OF CHICAGO, ILLINOIS, ASSIGNORS TO TEMPLETON, KENLY & CO. LIMITED, OF CHICAGO, ILLINOIS, A CORPORATION OF ILLINOIS

RAIL PULLER AND EXPANDER

Application filed November 21, 1931. Serial No. 576,474.

This invention relates to improvements in rail puller and expander and it consists of the matters hereinafter described and more particularly pointed out in the appended 5 claims.

The puller and expander with which our invention is more particularly concerned, is of the kind employed in railway track maintenance for lining crossings, inserting and renewing fibre and like end posts and testing the holding power of rail anchors or anti-creepers. Devices as now made for this purpose, include a pair of nut-like housings disposed upon one side of the web of the meeting 10 ends of abutting rails and these nuts receive the ends of an actuating screw. This screw has oppositely threaded ends and a ratchet wheel midway between its ends with which a lever receiving socket, carrying a reversible 15 pawl is associated. When the device is employed in lining crossings and pulling together and expanding rails, a splice bar is also employed and is disposed upon the other side of the abutting rail ends and bolts carried by 20 the housings extend through said splice bar to receive nuts to clamp the parts together. When the pawl associated with the lever socket and ratchet has been properly manipulated and the lever is actuated, the ends of 25 the rails to which the device is applied are pushed apart or expanded in one instance and pulled together or contracted in the other instance. When the device is employed in applying end posts between the rail ends, the 30 splice bar on that side of the rail ends opposite the nut-like housing is not employed and the associated nuts are simply reversed upon the clamping bolts.

Such a device has certain inherent objections which our improved rail puller and expander overcomes. When the device is employed in applying end posts and the splice bar before mentioned, it is apparent that the 35 great tension of the rails when pushed apart is taken up by the screw alone, with the result that the screw often buckles and then binds in the nut-like housings. As the space in which the device is employed is quite limited 40 ed, increasing the diameter of the screw to

overcome this buckling action is impractical if not impossible.

The primary object of the invention is to improve the structure and arrangement of the associated parts, so that it is unnecessary to remove any component parts thereof, when the device is under the tension of expanded rail ends for the insertion of an end post, thus retaining the greatest strength in the device when most needed and eliminating any buckling action on the screw and its subsequent binding in the nut-like housings. 55

A further object of the invention is to provide a device of this kind which includes a channel-shape bar to receive the nut-like 60 housings and which bar is so formed that said housings can move thereon in the operation of the device and also acts to prevent the buckling of the screw and at the same time leave the other side of the rail free for the 65 lateral insertion of the end post.

The above mentioned objects of the invention, as well as others, together with the many advantages thereof, will more fully appear 70 as we proceed with our specification. 75

In the drawing:—

Fig. 1 is a perspective view of our improved rail puller and expander as when applied to abutting rail ends for the purpose 80 of pushing the rail ends apart for the insertion of an end post therebetween.

Fig. 2 is a horizontal longitudinal sectional view through the same and said abutting rail ends.

Fig. 3 is a transverse vertical sectional view through the same as taken on the line 3—3 of Fig. 2. 85

Fig. 4 is a perspective view of a certain brace bar embodied in our improved rail puller and expander and which will be more fully 90 referred to later.

Referring now in detail to that embodiment of the invention illustrated in the accompanying drawing: 1 and 2 indicate respectively abutting rail ends, which are to be spread apart or expanded for the purpose of inserting an end post 3 in the space or gap therebetween. 95

The rails which are of standard cross section, each include a base flange 4, an upright 100

web 5 and a head 6, the end post 3 which is usually made of fibrous material, having a similar cross section.

The device comprises as a whole, a pair of 5 housing-like nut members 7—7 each including a head 8 on one end of a base flange 9 and the heads 8 are internally and longitudinally threaded in the usual manner; that is, one has a right hand thread and the other 10 has a left hand thread therein to receive the ends of an oppositely threaded screw 10. Each head is connected to the other end of the base by top and bottom flanges 11 and in each base is a longitudinal slot 9a.

15 Between the threaded parts of the screw 10 is fixed a ratchet wheel 12. This ratchet wheel is disposed between the spaced arms 13 of a socket member 14 into which a lever (not shown) is inserted for actuating the 20 same. Also pivoted between said arms 13 is a reversible pawl 15, which is yieldingly held in the proper ratchet wheel engaging position by means of a spring pressed plunger 16 in the end of the socket member between 25 said arms. Said pawl 15 is pivoted on a cross pin 17 and when it is desired to turn the screw in one direction, or the other, the pawl is manually swung to engage the desired tooth thereof, with said ratchet wheel.

30 In the head end of each housing-like nut member 8 is anchored a threaded stud 18 preferably secured in place by a cross pin 19 and associated with the slotted end of the base of each housing member is a bolt 18a.

35 Instead of having the housings engaged directly with the side of the web of said rail ends and applying a splice bar to the other side thereof, as heretofore, I provide the following:—

40 20 indicates a housing receiving and guiding brace bar of such a channel-shaped cross section as to include a web 21, a base flange 22 and a top flange 23, the latter being of a depth less than the former. One face of the 45 web of said bar is made of a contour along the inside fitting the side of the web of a rail and is flat along its other or outside, while the flanges 22 and 23 are inclined in accordance with the top surface of one side of the 50 base and the bottom surface of one side of the head. The bar however, is of such perpendicular dimensions that said flanges have a slight clearance with respect to said base and head. In each end of the web of this 55 bar are longitudinal slots 24 of substantial length and the outer face of said web above and below said slots are formed to provide top and bottom longitudinal surfaces 25 upon which the nut-like housings engage.

60 Assume now that it is desired to insert an end post 3 between said rail ends. The bar 20 is placed upon one side of the rail ends and then the two housings 7 which are mounted on the screw 10 are engaged with 65 their bases against the surfaces 25 of the

brace bar. The studs 18 carried by said housing-like nut members are then inserted through the slots 24 of the bar and through the endmost holes 5a in the webs of said rail. The bolts 18a which extend through the slots 70 9a in the base of the housing-like members 7 have rectangular heads engaging the flanges 11 on said housing-like members to prevent turning of said bolts, are then inserted through the slots 24 in the brace bar and through the holes 5b in the rail ends. By means of the slot arrangement in the base of the housing-like nut members and in the brace bar, they will accommodate different 75 spacings between the holes 5a—5b in the rail ends.

The studs 18 and bolts 18a are of such length that the plain unthreaded portions thereof extend beyond the opposite side of the rail ends and upon the threaded ends thereof, nuts 26 are applied. Each nut is preferably made from square stock and is relatively long and in each end the nut is enlarged interiorly as at 26a so as to overhang a part of the unthreaded end of the stud or bolt with which it is associated. Thus when the nuts 26 are tightly drawn up on the studs and bolts, the associated housing-like nut members 7—7 are tightly secured to the rail ends. In applying the parts in position, it is desirable that the surfaces 25 of the brace bar be lubricated.

When the pawl 15 has been properly set, an up and down movement on the lever inserted in the socket member 14 will turn the screw 10 in the proper direction to cause the housing-like nut members to travel outwardly toward the ends of the screw, sliding with a guided bearing engagement on the surfaces 100 25 of the brace bar. As the rail ends are connected to the housing-like nuts, by the studs 18 and bolts 18a it is apparent that the rail ends are forced endwise apart or expanded. When the space or gap between the rail ends is wide enough to permit the insertion of an end post 3, this is done from that 105 side of the rail ends, opposite the housing members. After the end post has been inserted, the pawl 15 is manipulated to cause the screw to move said housing-like nut members toward each other and this pulls or draws the rail ends together after which the usual splice bars are applied to finish up the joint.

110 It is apparent that when the rail ends are thus expanded, a heavy tension is imposed upon the screw and heretofore in structures for like purpose, such a tension buckled or bent the screw so that a binding action developed which made the device difficult to operate if not impossible.

115 Such a buckling of the screw in the present instance is eliminated because of the bracing action of the bar which holds all parts in their true aligned position. Thus by providing the bar 20 a twofold function is had in 120 125

that it holds the rail ends in proper alignment and also forms a guide upon which the housing-like nut members have a guided movement. Because of its channel-like cross sectional shape, it can be made of relatively light stock and its resistance to bending is such as to prevent any buckling thereof. The device may also be employed with equal facility in lining crossings and pulling or expanding rails as well as for testing the holding powers of rail anchors.

While in describing the invention, we have referred in detail to the form, arrangement and construction of the various parts thereof, the same is to be considered merely as illustrative only, so that we do not wish to be limited thereto except as may be specifically set forth in the appended claims.

We claim as our invention:—

1. A device of the kind described comprising housing members adapted to be disposed in longitudinally spaced relation upon one side of abutting rail ends and each to be secured to an associated rail end, means including a screw operatively engaged with the housing members for moving them away from and toward each other and a member disposed upon the same side of and overlapping said rail ends and spanning the gap between them for guiding said housing members in their movement and for bracing the screw against bending under the action of the expended rail ends.

2. A device of the kind described comprising housing members adapted to be disposed in longitudinally spaced relation upon one side of abutting rail ends and each to be secured to an associated rail end, means including a screw operatively engaged with the housing members for moving them away from and toward each other and a member disposed between said housing members and rail ends and spanning the gap between said rail ends and providing a guide upon which said housing members may be moved, said member also bracing the screw against bending under the action of the expanded rail ends.

3. A device of the kind described comprising housing members adapted to be disposed in longitudinally spaced relation upon one side of abutting rail ends and each to be secured to an associated rail end, means including a screw operatively engaged with the housing members for moving them away from and toward each other and a member disposed on the same side of said rail ends and engaged with the web thereof and spanning the gap between them, said member being formed to provide a surface upon which said housing members have a guided sliding movement and acting to brace the screw against bending under the action of the expanded rail ends.

4. A device of the kind described comprising

housing members adapted to be disposed in longitudinally spaced relation upon one side of abutting rail ends and each to be secured to an associated rail end, means including a screw operatively engaged with the housing members for moving them away from and toward each other and a channel member disposed between said housing members and rail ends and spanning the gap between said rail ends, said channel member including top and bottom flanges and a web, one surface of the latter being formed for a snug engagement with said web of the rail ends and the other side of which channel member being formed to provide a surface upon which said housing members may move in a guided path.

5. A device of the kind described embodying therein housing members disposed in longitudinally spaced relation, means including a screw operatively engaged with the housing members for moving them away from and toward each other, a bracing member disposed between said housing members and the ends of abutting rail members, said member being formed to provide a guided movement for said housing members and having longitudinal slots therein, threaded devices carried by the housing member and extending through said slots in said bracing member and through openings in said rails and nuts on said threaded devices on the other side of said rail ends.

6. In a device of the kind described, housing members adapted to be disposed upon one side of abutting rail ends, means including a screw operatively engaged with the housing members for moving them toward and away from each other, devices carried at one end by said housing members and extending through said rail ends and threaded at their ends beyond said rail ends and nuts disposed upon said devices and engaged with the other side of said rail ends and having enlarged end openings to surround and accommodate unthreaded parts of said devices near said rail ends.

7. In a rail puller and expander, a bracing bar adapted for engagement with one side of abutting rail ends, said bar including a web and top and bottom outwardly extending flanges, said web having longitudinal slots therein, one face of said web being formed for a snug engagement with one side of the web of said rail ends and the other side being formed with longitudinally extending guide surfaces, one on each side of said slots.

In testimony whereof, I have hereunto set my hand this 7th day of October, 1931.

FRANK J. JAKOUBEK.

In testimony whereof, I have hereunto set my hand this 7th day of October, 1931.
